A. SMITH,

MANUFACTURE OF PERFORATED METAL FOR DRAINAGE CASINGS, SCREENS, &c.

APPLICATION FILED JULY 23, 1914. RENEWED DEC. 5, 1917.

1,271,787.

Patented July 9, 1918.

FIG. 1.

78-163-2

7/15.3.

FILED 4.

A cross-sectional diagram of a composite material. It shows a solid base layer at the bottom, followed by a hatched layer. An arrow labeled '8' points to the interface between these two layers.

A horizontal strip of material, possibly a fabric or a technical drawing, featuring a repeating pattern. The pattern consists of a series of diagonal hatching lines on a white background, followed by a solid white segment, and then a series of diagonal hatching lines on a white background. This sequence repeats across the entire strip.

UNITED STATES PATENT OFFICE.

ANDREW SMITH, OF SAN MATEO, CALIFORNIA.

MANUFACTURE OF PERFORATED METAL FOR DRAINAGE-CASINGS, SCREENS, &c.

1,271,787.

Specification of Letters Patent.

Patented July 9, 1918.

Application filed July 23, 1914, Serial No. 852,654. Renewed December 5, 1917. Serial No. 205,685.

To all whom it may concern:

Be it known that I, ANDREW SMITH, a citizen of the United States, residing at San Mateo, in the county of San Mateo and State of California, have invented certain new and useful Improvements in the Manufacture of Perforated Metal for Drainage-Casings, Screens, &c., of which the following is a specification.

10 This invention relates to the manufacture of perforated metal plates or sheets which are especially adapted for use in making casings for drainage purposes, such as well curbing for lining oil and water wells, tiling, culverts and also for screens and strain-
ers in various arts, etc.

15 The main purpose of my invention is to provide perforated metal sheets or plates having smooth-walled slots or openings of any desired width from the narrowest slit and to facilitate the manufacture of such plates. A further object is to provide a process of manufacturing slotted plates in which the apertures may be cut by the use 20 of gangs of planing or milling tools or other cutting implements.

25 For the purpose of clearly disclosing this invention reference is made to the accompanying drawing in which—Figure 1 is a cross-section showing the edge or thickness of a metal sheet; Fig. 2 is the same after being corrugated; Fig. 3 is a perspective view of the corrugated plate showing the manner of cutting the slots by means of successive gangs of tools; Fig. 4 is a longitudinal section of the slotted plate after the corrugations have been pressed back into the plane of the sheet; Figs. 5 and 6, are transverse sectional views of slotted plates 30 showing different shapes of slots and the corresponding cutting tools; and Fig. 7 is a sectional view of a perforated plate bent into semi-circular shape to show the manner of forming drainage casings.

35 The first step in the process of slotting sheet metal according to this invention consists in corrugating the metal and preferably with flattened convexities 3, upon one side; as indicated in longitudinal section in Fig. 2. It will be observed that the metal in the series of convex portions upon the upper side of the sheet extends entirely 40 above the plane of the concave portions 2, and that cutting tools moving longitudi-

nally of the plate can pass entirely through the metal walls of the convex portions while still passing over the concave portions. It will also appear that by flattening the corrugations which are cut by the tools, the slots will be substantially of uniform width throughout their extent, which is very desirable in drainage casings.

45 The slots are cut in the sheet in parallel rows in the manner indicated in Fig. 3, by gangs of cutting tools 6, which move over the sheet in a plane parallel therewith. The slots are cut in successive stages, which may be done by adjusting the gang of cutters to cut deeper at successive movements, but I prefer to employ a series of sets or gangs 50 of tools which follow in succession, each succeeding gang cutting deeper into the metal than the preceding gang and being also preferably so shaped as to progressively coöperate in forming the desired cross-sectional shape. When the slots are to be V-shape in section, as illustrated at 8 in Figs. 3 and 5, each succeeding set or gang of tools is more pointed and longer than its predecessor; but when the slots are to be of uniform width through the section or thickness 55 of the sheet, the gangs of tools 6' will be of the shape as shown in Fig. 6, and merely differ in the depth of cut.

60 Drainage casings, such as well curbing, culverts, tiling, etc., may be formed from sheets perforated with slots, as shown in Fig. 3, by bending the sheets into tubular or pipe form, the upper side in said figure forming the inner side of the casing and the corrugations 2, constituting convex bands encircling the pipe. If, however, a smooth casing is desired, the slotted plate shown in Fig. 3, is subjected to a pressing or rolling operation to force the corrugations 2 back into the plane of the sheet, as shown in longitudinal section in Fig. 4, and in cross section in Fig. 5. If the sheets formed in this manner are bent into tubular form in the manufacture of drainage casings with the upper side in said illustrations constituting the inside of the casing, the slots will be narrowest at the outside, becoming wider in passing through the wall of the casing as shown in Fig. 7. The advantage of V-shaped slots lies in the fact that any particles which can pass through the slots from the narrow outside opening

will immediately pass into an ever widening channel thereby eliminating any danger of clogging the slots.

Having now described the process of forming slotted plates or sheets according to my invention and having pointed out some of the uses of resulting product, I claim:—

- 5 1. The process of making perforated metal sheets or plates for strainers, drainage casings, etc., comprising forming a series of corrugations in the metal plate, thereby forming alternate elevations and depressions therein, cutting a series of parallel slots through the elevations, and forcing the corrugations into the plane of the plate.
- 10 2. The process of making perforated metal sheets or plates for strainers, drainage casings, etc., comprising forming a series of corrugations in the metal plate, to raise portions of the metal above the plane of the

intervening portions, and cutting a series of parallel slots through the raised portions transversely of the corrugations.

3. The process of making perforated metal sheets, or plates for strainers, drainage casings, etc., comprising forming a series of corrugations in the metal plate, to raise portions of the metal above the plane of the intervening portions, said raised portions being flattened substantially throughout their extent, and cutting a series of parallel slots through the raised portions transversely of the corrugations.

25 30 In testimony whereof I affix my signature in presence of two witnesses.

ANDREW SMITH.
